SHEET METAL LINK AND CHAIN MADE THEREOF

Walter Bischoff, Berkeley Heights, N. J.

Application March 8, 1955, Serial No. 492,925

9 Claims. (Cl. 59—80)

The invention relates in general to jewelry and has particular reference to ornamental chain to be used in the manufacture of bracelets, necklaces and similar articles.

In chain type jewelry, such as bracelets and necklaces, ornamental appearance of the finished product is of primary importance, but there are certain functional requirements which must be satisfied in order that the article of jewelry may be fully adapted for wear in the intended manner. Chain to be incorporated in a necklace, for instance, must possess sufficient flexibility to permit the usual catenary suspension from the neck of a wearer. On the other hand, most wearers prefer a bracelet that is not too closely skin-conforming so usually choose one of the comparatively stiff bangle or circlet type. For these reasons, it has been impracticable prior to my present invention to provide a chain structure that will have both the flexibility desired for necklace manufacture and the stiffness for use in a bracelet. It, therefore, has been my express purpose to devise a highly ornamental chain structure which is a compromise between flexibility and stiffness and thus is equally adaptable for incorporation in articles of jewelry of both chain types enumerated above.

In accordance with my primary object, the improved ornamental chain is composed of links of such structure that when the radius of curvature of the chain is large, as in the natural draping of a necklace, adequate flexibility is afforded, whereas, when the radius is reduced to produce a bracelet, the chain automatically becomes progressively more stiff as the degree of curvature approaches that required in a bracelet. In other words, the new chain structure may be termed "auto-stiffening." To be more explicit, all links in the chain are of identical structure and each one has a wedge, or cam, element for frictional engagement with a coacting part of an adjoining link, whereby bending of the finished chain beyond the degree of curvature natural in the wearing of a necklace will result in increasing resistance to flexion, or auto-stiffening.

Another object of the invention is the provision of a link structure in which the wedge element serves as means to interlock adjoining links during assembly in fabrication of a chain and wherein each link is of resilient material and of such formation that it may be flexed by use of simple tweezers or pliers during assembly or disassembly to lock or unlock its wedge element with respect to the next adjoining link of the chain.

Initial assembly of my novel links produces a chain of substantially square cross-section and one which is very pleasing in appearance. However, in the course of experimentation with a view to varying the cross-sectional form, it was discovered that the interengaged links of the square chain were readily susceptible to deformation in a manner whereby the cross-sectional form could be changed to that of a circle or an ellipse without detracting from the general ornamental effect or from the desired compromise between flexibility and stiffness. A

2

further object of the invention, therefore, is the provision of an effective method of modifying the cross-sectional form of the improved chain.

The foregoing and other objects, advantages and features of the invention will be more fully understood as the following specific description is read in connection with the accompanying drawing, in which:

Fig. 1 is a plan view of one of the links employed in the improved chain; Fig. 2 is a side elevation of the same; and Fig. 3 is an end projection of the link when slightly tilted in the position assumed in relation to the chain axis after assembly with other component links.

Fig. 4 is a fragmentary side elevation of a section of square chain produced by assembling plural component links of the structure shown in Figs. 1 to 3; Fig. 5 is a longitudinal section of the same; and Fig. 6 is a transverse section on line 6—6 of Fig. 4.

Fig. 7 is a fragmentary side elevation of a section of chain after conversion from square to circular cross-section; and Fig. 8 is a similar view of a section of chain after conversion from square to elliptical cross-section.

Fig. 9 is a diagrammatic view representing the method of forming the round chain depicted in Fig. 7; and Fig. 10 is a similar view showing the method of producing the elliptical chain shown in Fig. 8.

Referring now in detail to the drawing, wherein like reference characters designate corresponding parts in the several views, the specific structure of the link which has been devised for use in production of a chain of the desired appearance and physical characteristics is shown separately in Figs. 1 to 3, inclusive. While it may be practicable to form the proposed link from wire stock or by molding process, it is preferred to stamp it out of thin sheet material, such as gold, silver or other precious metal, by use of suitable dies (not shown).

Each link in its preferred form includes a substantially square-cornered body 10 that has the general shape of the letter C, which is shown reversed in arrangement in Fig. 1. For convenience of reference, the front face of the link as it appears in Fig. 1 will be considered as the upper face and the stem of the letter C, at the right in the said figure, will be termed the front portion or edge of body 10 in relation to the chain axis and to the end of the latter which is formed first in the link-assembling operation. The space which intervenes between the arms of the letter C and opens through the rear edge of body 10 is of functional utility and will be known as medial slot 11. The dimensional relations of medial slot 11 with respect to other parts of the link structure will be defined presently.

Each arm of the letter C is provided with a longitudinal slot 12 paralleling medial slot 11 and which will be called a side slot in relation to the major link axis.

On the front edge of body 10, there is an integral and medially located, forwardly extending wedging element 13 which preferably is substantially triangular in form and presents an acute nose or point. Because, in assembling each link with others to form a chain, one arm of the said link and wedging element 13 must be capable of being threaded or hooked through the side slot 12 of an adjoining link, the distance between the nose of wedging element 13 and the inner end of medial slot 11 should be slightly less than the length of each side slot 12 to allow sufficient end clearance. For the further reason that a pair of links will be engaged within medial slot 11, this slot should be more than twice as wide as side slot 12.

Referring in particular to Fig. 2, it will be observed that body 10 of each link is curved from front to rear in such a manner that it is upwardly convex and concave underneath. Moreover, wedging element 13 is upturned at a slight angle to the chord of body curvature. These last-mentioned structural features, in cooperation with

the inherent resilience of the comparatively thin material of which the link is composed, render the wedging elements 13 of all the combined links capable of performing the dual functions of automatically increasing the stiffness of the chain when it is bent beyond a certain degree of curvature and of locking the respective links in assembled engagement with adjoining links. The precise manner in which these useful functions are performed will now be described.

The mode of link assembly in making up the chain in its square cross-section form should be understood by referring to Fig. 4 in particular. Assuming that the two links shown edgewise in that figure next to the two broken links at the right end of the chain section are the first links in a new chain, these two edgewise links are held in closely abutting relation instead of angularly arranged as shown. Then, one other link is turned at right angles to the two first-mentioned links and is hooked through registering side slots 12 at one side of the medial slots 11 of said two links, which operation will bring the ends of the corresponding arms of the latter into medial slot 11 of the said other, or third-mentioned, link. In doing this, the upturned wedging element 13 of the third-mentioned link will not pass freely through the side slots 12 of the first-mentioned links, because the vertical projection of said upturned wedging element exceeds the width of each side slot 12. It is necessary, therefore, to squeeze the front edge portion of the third-mentioned link between the jaws of a pair of tweezers, or pliers, and thereby partially flatten the link until the vertical projection of wedging element 13 is reduced so that it will pass through slot 12. In assembling a fine chain, a holding tool, such as tweezers or pliers, is required to pick up and manipulate each link, so it is the practice to engage the front portion of each link at the angle between its body 10 and wedging element 13 by the jaws of the same, so the application of sufficient pressure for securely gripping the link will serve to flatten out the angle of upturn enough to permit said wedging element to clear the edges of side slot 12. After the third-mentioned link has been threaded through the side slots 12—12 of both first-mentioned links and the holding tool has been disengaged with the former, it will spring back into its original form and wedging element 13 thereof will become locked automatically against disengagement with the two first-mentioned links. Re-use of the holding tool will be required thereafter to disassemble any link from locked engagement with other adjoining links in the chain.

After the third-mentioned link has been assembled in interlocking engagement with the two first-mentioned links, a fourth link is paired up with said third-mentioned link by threading it through the remaining unoccupied and registering side slots 12—12 in said two first-mentioned links, and in the same way with the aid of a holding tool. Thereafter, the process is repeated as described until the desired length of chain is completed. As each pair of additional links become assembled, it is the practice to rotate the chain through an angle of ninety degrees to facilitate assembly of the succeeding pair of links.

The manner in which the wedging elements 13 automatically stiffen the chain when flexed laterally to a degree exceeding that of normal use in a large radius article of jewelry, such as a necklace, will be understood upon particular reference to Fig. 6. For instance, supposing that the upper and lower links of the pair represented in full lines become oscillated during lateral flexion of the chain on a vertical axis, the wedging elements of said links will become frictionally engaged with the abutting edges of the respective side slots 12—12 in one of the right and left pair of links shown in cross-section depending upon the direction of flexion. The result will be progressively increased frictional resistance to flexion as the wedging elements become more deeply wedged into the side slots. Upon restoration of the chain to a more

nearly straight condition, frictional resistance will be relieved and the chain will become fully flexible again.

In order to convert the originally square chain C shown in Figs. 4 to 6 into a chain of pleasingly round cross-section, such as that shown in Fig. 7, the square chain is inserted between the forming dies 14—14 which have semi-cylindrical opposed faces of appropriate diameter, while being held with the diagonals of its square cross-sectional form at an angle of forty-five degrees to the direction of movement of the dies. When the dies 14—14 are then closed on each other, they will press the chain into round form as at C', in which action the links of the chain become deformed without detracting from the ornamental appearance of the chain as a whole.

Dies 15—15 having semi-elliptical faces are employed to convert a square chain C into a chain of elliptical cross-section as at C''. Before the dies are closed, the square chain C must be held with one diagonal in alignment with the direction of die movement.

It is to be understood that the present disclosure of the invention is an illustrative example and that various changes, modifications and alterations may be made in these structural embodiments which do not constitute departures from the spirit and scope of the invention.

I claim:

1. As an article of manufacture, a chain link comprising a substantially C-shaped body having a stem and parallel arms with a medial slot therebetween which is open at its end opposite to said stem, and a substantially triangular wedging element projecting from the stem of the body opposite to said medial slot with its nose facing away from the latter, the arms of the body being provided with closed side slots arranged substantially parallel to said medial slot and being slightly greater in length than the distance between the nose of the wedging element and the inner end of said medial slot.
2. As an article of manufacture, the chain link defined in claim 1, wherein the body is curved in the direction of the arms and slots.
3. As an article of manufacture, the chain link defined in claim 2, wherein the wedging element is bent oppositely with respect to the concave side of the curvature of the link body.
4. As an article of manufacture, the chain link defined in claim 3, wherein the body is made of thin resilient material and the projection of the wedging element angularly from the chord of curvature of the body exceeds the width of each side slot.
5. As an article of manufacture, the chain link defined in claim 1, wherein the body is made of thin resilient material and the projection of the wedging element angularly from the chord of curvature of the body exceeds the width of each side slot.

6. As an article of manufacture, the chain link defined in claim 1, wherein the medial slot is at least twice as wide as each side slot.
7. An auto-stiffening chain comprising plural interengaged links of identical structure, each link including a substantially C-shaped body having a stem and parallel arms with a medial slot therebetween which is open at its end opposite to said stem and a substantially triangular wedging element projecting from the stem of the body opposite to said medial slot with its nose facing away from the latter, the arms of the body being provided with closed side slots arranged substantially parallel to said medial slot and being slightly greater in length than the distance between the nose of the wedging element and the inner end of said medial slot, in the interengaged relation of the several component links of the chain the latter being arranged in side-by-side pairs with the links of each pair rotated about the chain axis substantially ninety degrees relative to the links of the next succeeding pair and having the arms of each link of any pair threaded through the registering side slots in corresponding arms of both

- links of an adjoining pair, whereby the arms of both links

of each pair are abuttingly confined in the registering medial slots of the adjoining pair of links, the chain thus produced being substantially square in cross-section.

8. An auto-stiffening chain as defined in claim 7, wherein each link is made from thin resilient material and the wedging element of each link is bent angularly with respect to the link body to such a degree that the projection of said element away from the body is greater than the width of each side slot in the body arms.

9. An auto-stiffening chain as defined in claim 8, 10

wherein the body of each link is curved longitudinally with the convex surface facing in the same direction as the angular bend in the wedging element.
